(57) **CLAIM**

The ornamental design for an integrated frame and curb box, as shown and described.

DESCRIPTION

FIG. 1 is a top, front and left side perspective view of the integrated frame and curb box of the present invention.

FIG. 2 is a bottom, front and left side perspective view of the integrated frame and curb box of FIG. 1.

FIG. 3 is a front elevational view of the integrated frame and curb box of FIG. 1.

FIG. 4 is a top view of the integrated frame and curb box of FIG. 1.

FIG. 5 is a right side elevational view of the integrated frame and curb box of FIG. 1.

FIG. 6 is a rear elevational view of the integrated frame and curb box of FIG. 1; and,

FIG. 7 is a bottom view of the integrated frame and curb box of FIG. 1.

The left side elevational view of the frame and curb box is a mirror image of the right side elevational view.

FIGS. 1 and 3-6 show portions of the integrated frame and curb box in phantom lines. The phantom lines show boundaries of the design and elements of the integrated frame and curb box that form no part of the claimed design.

1 Claim, 5 Drawing Sheets
